AUTOMATIC SHUT OFF FOR SWITCHES

John Ralph Haines, Tabernacle, N. J.

Application May 1, 1933, Serial No. 668,831

3 Claims. (Cl. 200—59)

This invention relates to an improved steering wheel actuated shut off for switches for use in connection with direction signals as installed on motor vehicles, and particularly in connection with the type of switch set forth and claimed in the application of John Ralph Haines, filed March 25, 1932, Serial No. 601,279.

In switches of the type disclosed in the above identified application manual means are employed for actuating the switch, either on or off. However in the present invention, while it is the purpose to operate the switch manually, it is also the purpose to restore it to initial position automatically through the medium of a steering wheel of the motor vehicle.

Another purpose is to provide a lever with means to clamp the lever on a rotating rod or shaft of the switch, said rod or shaft carrying the type of frog as disclosed in the co-pending application above identified.

Another purpose is to provide means mounted on the lever and cooperating with a segment guide on the top of the housing for the switch, said means adapted to engage with a notch in the segment for retaining the operating lever in its initial position, the ends of the segment guide acting to limit the lever in its two extreme positions, said positions being for holding movable contact arms of a switch frog in engagement with certain contact points of the switch.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawing and claimed.

In the drawing:—

Figure 1 is a view in elevation of a steering column with a steering wheel in section showing an automatic shut off as applied to a switch supported on the column.

Figure 2 is a plan view of the steering wheel with the automatic shut off applied to a switch.

Figure 3 is a sectional view on line 3—3 of Figure 2.

Figure 4 is a plan view of the switch showing the automatic shut off.

Figure 5 is a plan view with the cover of the switch casing removed.

Figure 6 is a detail view in elevation of a part of the switch casing showing a side view of the

shut off with the shut off lever in a position ready to be restored to initial position.

Figure 7 is a sectional view through one of the actuators 20 as applied to the spoke of the steering wheel.

Figure 8 is a sectional view on line 8—8 of Figure 7.

Referring to the drawing 1 identifies a casing for housing a switch such as disclosed in the above identified application, said switch including a switch frog 2 for cooperation with certain contacts for closing circuits to prove whether or not certain direction signals or lamps are lighted. The switch also includes a rod or shaft 3 extending through the top of the housing provided with a square or rectangular end 4, which enters a correspondingly shaped opening 5 of a switch lever 6. Where this correspondingly shaped opening is formed, the side of the lever is split as shown at 6', there being a screw 7 passing through the wall of the lever where said wall is spaced or split from the body of the lever. This screw tightens the wall toward the body of the lever, in order to clamp the lever on to the square or rectangular end of the shaft or rod. 15

The body of the lever is provided with a rectangular opening 8, in which a lug 9 of a detent 10 is pivoted upon a pin 11. The lever engages under an arch 12 of a curved segment 13, which is a part of the top of the housing. This curved 20 segment has a notch 14, which receives a V-shaped lug 15 carried by one end of the detent. The other end of the detent has a lug 16 with which one end of a coil spring 17 engages. The other end of the coil spring sets in a cavity 18 of 25 the body of the lever, thereby so tensioning the detent as to retain the V-shaped lug on one end of the detent in engagement with said notch 14. In this manner the lever is retained in its initial 30 position, with the switch frog in its initial 35 position.

The steering wheel 19' has two of its spokes provided with actuators 20. Each actuator consists of a block 21 including a band 22, which is secured upon the spoke as shown. This block 21 45 has a socket 23, in which a ball or spherical member 24 is mounted. The ball or spherical member is spring tensioned as shown at 25 and is adapted to ride over the V-shaped lug 26 on the upper face of the detent opposite the V-shaped lug 15, when moving the steering wheel in one direction, that is to say, when the switch lever has been actuated to its limiting position, for either having operated the switch when being moved to prove certain signals, or when having been moved 50 55

to prove certain other signals. The spring tensioned ball or spherical member upon return of the steering wheel to its initial position for driving straight ahead, after having actuated the 5 switch, the spring tensioned ball or spherical member engages with the V-shaped lug on the upper face of the detent, for restoring the lever to its initial position.

The invention having been set forth, what is 10 claimed is:

- 10 1. A direction indicator switch comprising a steering-column-carried casing, a switch lever having a pivotal mounting on top of the casing for swinging movement forwardly or rearwardly 15 to close either of two direction indicating circuits, the casing on the top being provided with an arcuate segment straddling the lever to limit both the forward and rearward movements of the latter, a detent movably mounted on the lever 20 and extended beyond the mounting to ride on the segment, a spring connected with the detent and carried by the lever to yieldingly impel the detent toward the segment, the segment having a centrally disposed notch and the detent having 25 a lug engageable in said notch to yieldably retain the lever in neutral position, and a steering-wheel-carried actuator for movement over the casing in rotation of the steering wheel, the detent being disposed in the path of said actuator 30 so that the latter may impart movement to the lever except when the lug is engaged in the notch of said segment.
2. A direction indicator switch comprising a steering-column-carried casing, a switch lever 35 having a pivotal mounting on top of the casing for swinging movement forwardly or rearwardly to close either of two direction indicating circuits, the casing on top being provided with an arcuate segment straddling the lever, a detent 40 having a pivotal mounting intermediate its ends, the detent being carried by said lever with one end overhanging the segment, a spring interposed

between the other end of the detent and said lever to yieldingly impel the overhanging end of the detent toward the segment, the segment having a centrally disposed notch and the detent having a lug engageable in said notch to yieldably retain the lever in neutral position, and a steering-wheel-carried actuator for movement over the casing in rotation of the steering wheel, the detent being disposed in the path of said actuator so that it may impart movement to the lever except when the lug is engaged in the notch of said segment. 5

3. A direction indicator switch comprising a steering-column-carried casing, a switch lever having a pivotal mounting on top of the casing 15 for swinging movement forwardly or rearwardly to close either of two direction indicating circuits, the casing on the top being provided with an arcuate segment straddling the lever to limit both the forward and rearward movements of the 20 latter, a detent mounted on the lever and extended beyond the mounting to ride on the segment, a spring connected with the detent and carried by the lever to yieldingly impel the extended end of the detent toward the segment, 25 the segment having a centrally disposed notch and the detent having an element engageable in said notch to yieldably retain the lever in neutral position, and a steering-wheel-carried actuator for movement over the casing during rotation of the steering wheel, the detent being disposed in the path of said actuator so that the latter may 30 impart movement to the lever except when the element is engaged in the notch of said segment, the actuator embodying a spring-pressed 35 ball to roll over one face of the detent when the lever is at either end of the segment when the actuator is between the ends of the segment but moving toward that end at which the lever is disposed. 40

JOHN RALPH HAINES.
